UNITED STATES PATENT OFFICE.

ROBERT C. FUNKE, OF PHILADELPHIA, PENNSYLVANIA.

HAMMOCK-STAND.

No. 801,582.

Specification of Letters Patent.

Patented Oct. 10, 1905.

Application filed January 20, 1905. Serial No. 241,952.

To all whom it may concern:

Be it known that I, ROBERT C. FUNKE, a citizen of the United States, and a resident of Philadelphia, in the county of Philadelphia and 5 State of Pennsylvania, have invented certain new and useful Improvements in Hammock-Stands, of which the following is a specification.

The object of the present invention is to provide a simple, reliable, attractive, and comparatively inexpensive knockdown adjustable hammock-stand which can be safely employed with hammocks of various sizes and may be packed in an exceedingly small compass.

15 The invention comprises the improvements to be presently described and finally claimed, and it will be more fully understood by reference to the accompanying drawings, in which—

Figure 1 is a view, partly in section and with 20 portions removed, of a hammock-stand embodying features of the invention. Fig. 2 is a front view, partly in section, drawn to an enlarged scale and illustrating one of the bases shown in Fig. 1; and Figs. 3 and 4 are respectively a sectional and a plan view of bases 25 embodying a modification of the invention.

In the drawings, 1 and 2 are a pair of supports arranged at an outward inclination with respect to each other. They are provided with 30 laterally-extending bases 3, perforated, as at 4.

5 is a horizontal bar which extends through the perforations 4.

The hammock 6 is suspended from the supports, and the latter may be slipped along the 35 bar 5, so as to secure the proper adjustment. Whenever weight is brought to bear upon the hammock, the effect is to bend the walls of the perforations 4 upon the rod 5 in such a way that they are firmly and safely held. The supports are shown to consist of arms, which are 40 detachably inserted in sockets 7 in the bases 3.

As illustrated in Fig. 2, the lateral extensions 8 of the bases are integral and may, together with the rest of the base, be constructed 45 of wood, the edge 9 being beveled, so as to rest upon the ground or other foundation.

As shown in Figs. 3 and 4, the base consists 50 of a casting 10, which may be of malleable iron and of a bar or strip of wood 8^a, arranged crosswise of the same, so as to constitute lateral projections. The form of the casting 10 is shown in the drawings, and it may be fitted with a set-screw 11, which is a convenient

provision when the stand is to be moved about, although, as has been explained, it is 55 unnecessary for the purposes of supporting the weight which is placed upon the hammock. 12 represents screws or the like which serve to hold the bar or strip, as of wood, 8^a to place. 60

To knock down or take the stand apart, it is only necessary to detach the arms from the socket 7 and to slip the bases 3 off the bar 5, and in the case of the construction shown in Figs. 3 and 4 the strip 8^a may be detached 65 from the casting 10.

To those skilled in the art to which the invention relates modifications may be made in details without departing from the spirit thereof. Hence the invention is not limited 70 further than the prior state of the art may require; but,

Having thus described the nature and objects of my invention, what I claim as new, and desire to secure by Letters Patent, is— 75

1. A knockdown adjustable hammock-stand comprising a pair of supports arranged at an outward inclination and provided with perforated bases, and a horizontal bar extending through said perforations, substantially as described. 80

2. A knockdown adjustable hammock-stand comprising a pair of supports arranged at an outward inclination and provided with laterally-extending perforated bases, and a horizontal bar extending through the perforations, 85 substantially as described.

3. A knockdown adjustable hammock-stand comprising a pair of perforated bases provided with sockets, arms fitted to said sockets, 90 and a bar extending through the perforations and the bases whereby the latter are held at an outward inclination, substantially as described.

4. A knockdown adjustable hammock-stand comprising a pair of castings provided with perforations and with inclined sockets, strips applied to said bases, arms fitted to said sockets, and a bar extending through the perforations in the bases, substantially as described. 95

In testimony whereof I have hereunto signed my name.

ROBERT C. FUNKE.

In presence of—

W. JACKSON,
K. M. GILLIGAN.
